BALLAST RESISTANCE

Seitoku Hamada, Tokyo, Japan, assignor to General Electric Company, a corporation of New York

Application November 28, 1933, Serial No. 700,091
In Japan May 30, 1933

2 Claims. (Cl. 201—63)

This invention relates to ballast resistances, and it has for its object the provision of an improved device of this character wherein the current rating of the resistance is adjustable over a relatively wide range of current values.

Ballast resistors heretofore known usually comprise a resistance element, such as an iron wire, sealed into a fluid-tight envelope or tube that is filled with a suitable non-oxidizing medium such as hydrogen. As is well known, the resistance at a certain critical temperature varies with temperature so rapidly that, as the voltage across the resistance varies, the current remains practically constant; that is, after a certain temperature has been reached, the ballast resistance will maintain a substantially constant current as the voltage across the resistance varies within a certain range.

Ballast resistors heretofore known have been designed for a specific application, i. e., have been designed to hold a single predetermined ballasting current. Heretofore, it has been impossible to adjust these devices to vary the current ratings after they have been made. However, in some instances, the resistors may be used in parallel with shunting resistances across the load to vary the current, or with series resistors to vary the voltage rating.

Moreover, it has not been possible heretofore to make a ballast resistor that will ballast relatively small currents.

This invention, in one of its aspects, contemplates the provision of a ballast resistor which is adjustable to hold various constant currents within a rather wide range, and moreover, a resistor which will function to ballast a much smaller current than has been possible heretofore.

It is another object of this invention to provide a ballast resistor that is not influenced by variations in the external temperature.

The ballast resistor made in accordance with this invention comprises a resistance element having a balancing function, and a second resistance element having a heating function arranged in thermal relation with the ballasting resistance so as to apply heat to the ballasting resistance and thereby vary its ballasting function. Both the ballasting element and the heating element are enclosed in a fluid-tight envelope or tube which contains a relatively low pressure non-oxidizing atmosphere.

For a more complete understanding of this invention, reference should be had to the accompanying drawing in which the single figure is a view in elevation of a ballast resistance ar-

ranged in accordance with this invention, portions being broken away so as to illustrate certain details of the construction.

Referring to the drawing, this invention is shown as applied to a ballast resistance comprising a ballast resistance element 10 wound upon a suitable insulating supporting cylinder 11. The resistance element 10 preferably will be made of iron, but may be made of nickel, or any other suitable metal which has the desired ballasting function.

The supporting cylinder 11 is supported within a suitable envelope or tube 12 which preferably will be made of glass. As shown, the cylinder 11 is rigidly secured to a suitable base 12a of the tube.

Suitable means are provided for applying heat to the resistance element 10 in addition to that which it receives from the current flowing through it. This auxiliary heating means comprises a resistance wire 13 which may be made of any suitable material, but preferably will be made of tungsten. The element 13, as shown, has substantially a hairpin shape, the two legs of the hairpin being received in suitable spaced parallel apertures 14 arranged longitudinally in the supporting cylinder 11.

The ends of the ballast resistor 10 are connected to suitable terminal members 15 electrically connected to a pair of terminal pins 16. The ends of the resistance 13 are connected to terminal wires 17 electrically connected to a pair of terminal pins 18.

It will be understood that the terminals 16 of the resistance element 10 will be connected in the load circuit which is to be controlled, and the terminals 18 for the resistance heating element 13 will be connected with a suitable source of electrical supply, the voltage of which preferably will be adjustable so that the heating element can be controlled to apply different quantities of heat to the ballasting resistance 10.

The envelope 12 is filled with a low pressure non-oxidizing atmosphere such as hydrogen.

As is well understood by those skilled in the art, when current is flowing through the resistance 10, and the resistance attains a critical temperature, the resistance varies with temperature so rapidly that, as the voltage across the resistance varies, the current remains practically constant. In other words, as the voltage across the terminals 16 increases from zero, the resistance of the element 10 increases slowly with temperature rise in the same manner as most metals. When the lower end of the operating range is 55

reached, the resistance of the element 10 increases quite rapidly with temperatures so that further increase in the voltage across the terminals 16 causes practically no further increase in the current. When the upper end of the operating range is reached, the resistance becomes nearly constant again. Between the lower and upper ends of the operating range the current remains substantially constant.

If now heat is applied to the resistance element 10 by the heating element 13 in addition to that which the element 10 receives by virtue of the current flowing through it, the lower end of the operating range will be reached when a smaller current is flowing through the resistance than would be the case if the temperature of the resistance element 10 were raised solely by the current flowing through it.

Consequently, the ballast resistor 10 will hold a constant current which has a lower value when receiving heat from the auxiliary heater 13, than when operating without the auxiliary heater.

In other words, the auxiliary heater 13 by supplying heat to the resistance 10 lowers the current value necessary to bring the temperature of the resistance to the lower end of its operating range. By controlling the heating element 13 to provide various temperatures, the resistance element 10 will ballast various constant currents, the value of the current ballasted, of course, depending upon the quantity of heat received from the auxiliary heating means 13.

As the quantity of heat imparted to the ballasting resistance element 10 from the auxiliary 13 determines the working character of the ballasting resistance, that is, its current rating, it is possible, of course, to obtain this current rating in terms of the heating current or voltage supplied to the heating element 13.

It will be apparent that when the auxiliary heater 13 imparts so much heat to the resistance element 10 as to raise its temperature rather close to the critical value, that is, to the lower end of its operating range, a very small current will supply sufficient additional heat to cause the temperature of the resistance to rise to the critical value. In other words, it is possible to ballast a very small current with the ballast resistor arranged in accordance with this invention. It has been

found experimentally that whereas the minimum current that can be maintained by ballasting resistors heretofore generally known is about 100 milliamperes, the ballasting resistor of this invention will ballast a current as small as a few 5 milliamperes.

It is to be noted also that the ballasting resistor arranged in accordance with this invention is not influenced by changes in the external temperature, because these changes affect both the 10 ballasting resistance wire and the heating resistance element; it has been found that the current rating of the ballasting resistor does not vary substantially even though the external temperatures change considerably.

While I have shown a particular embodiment 15 of my invention, it will be understood, of course, that I do not wish to be limited thereto since many modifications may be made, and I, therefore, contemplate by the appended claims to cover 20 any such modifications as fall within the true spirit and scope of my invention.

What I claim as new and desire to secure by Letters Patent of the United States, is:—

1. A ballast resistance comprising an insulating 25 rod having a plurality of longitudinal openings extending therethrough, supporting means for said rod arranged at one end thereof, a ballasting resistance element wound on said rod and having terminals adjacent to said end, and means for 30 maintaining said resistance element at a predetermined elevated temperature comprising a resistance heating element in each of said openings, said heating elements having terminals at said one end of the rod and being connected together 35 at the opposite end thereof.

2. A ballast resistance comprising a fluid tight envelope containing a non-oxidizing atmosphere, an insulating rod, means secured to one end of said rod for supporting the same in said envelope, 40 a ballasting resistance element wound on said rod and having both ends terminating at said end of the rod, and a heater for said resistance element comprising an elongated loop, said rod being provided with longitudinal openings receiving the 45 sides of said loop, the terminals of the loop extending from the said end of the rod.

SEITOKU HAMADA.
